MEANS FOR DESIGNING AND LAYING OUT
PLANS OF BUILDING

John D. McCall, Powell, Wyo.

Application December 17, 1947, Serial No. 792,238

4 Claims. (Cl. 33—1)

1

My invention relates to a new and improved means for designing and laying out the floor plans of buildings, and while not specifically limited thereto, is principally concerned with perfecting a means by which the prospective home owner, architect, or decorator may be enabled to visualize the projected construction, renovation, or decoration of a building in advance of its completion and may adjust the design or layout to meet the particular requirements of the ultimate user.

By means and methods known and used prior to my invention it is practically impossible for the layman to create an accurate floor plan or design due to his inability to use drafting equipment. Buildings heretofore constructed have been planned and plans have been drawn by architects or other designers well acquainted with such practice. Very few people are sufficiently skilled in reading plans to be able to fully visualize and appreciate the exact results in designing and layout that will be obtained in the completed building. As a consequence many expensive drawings and delays are necessitated as the designer tediously redraws his plans to meet the newly realized needs of the builder. In a great number of cases the inadequacy of a particular building is not recognized until the owner occupies the premises and attempts to arrange his furniture within the several rooms. It is then discovered that one room is too small and another too large, or that the placement of doors and windows in relation to the furniture is unsightly or inconvenient.

An object of my invention is to provide a means sufficiently simple and inexpensive of manufacture that the layman will be able to design the floor plan and layout of a prospective residence or other building.

Another object of my invention is to provide a means of designing and laying out floor plans by the use of which the average person will be able to see exactly and instantly the true relationship, one to another, of all of the component parts of the projected building, and the effect thereon of various arrangements and combinations of furnishings.

Still another object of my invention is to provide a means for designing and laying out floor plans so simple and inexpensive that the prospective home owner or builder will be able to conceive and execute his own plans for a projected residence or other building, making such changes and revisions as seem necessary both easily and quickly as the design or layout progresses.

2

A further object of my invention is to provide a means for designing and laying out floor plans such that an architect or designer may rapidly translate the ideas of a client into a readily understandable form that permits corrections and adjustments, so that the finally approved plan may be arrived at in a short time.

Yet another object is to provide a means for designing and laying out floor plans which will permit the accurate representation in reduced scale of building plans and the arrangement thereon of various articles of furniture.

My invention contemplates the use of a substantially flat base member in which a plurality of holes are drilled or impressed or otherwise formed. The holes are located or arranged in substantially parallel lines to substantially embrace the entire area of the board on which it is desired to plan, and these holes are of such diametrical dimensions and are spaced in such relation, one with respect to the other, as to permit fractional measurements that will correspond to the generally used architectural or engineering scales, such as $\frac{1}{4}$ "—1". With this in mind, and using the $\frac{1}{4}$ " scale, the holes will be drilled or located on $\frac{1}{4}$ " centers. A plurality of substantially cylindrical peg-like members of diametrical size slightly less than the size of the holes are provided to be readily inserted in and withdrawn from the holes, and these pegs can be inserted in selected openings with the ends extending upwardly above the surface of the base member to indicate dimensional points and outlines of exterior walls, partitions, and the like, to be laid out to indicate such points of a desired plan. For example, when the base member is made up for the scale of $\frac{1}{4}$ "—1", the pegs will be of a diameter representing the thickness of a wall of the finished plan of a building.

It is further contemplated that filaments, such as string, thread, or rubber bands of a color that contrasts with the color of the base member are to be provided to be wrapped about and stretched between portions of the peglike members which extend above the base, in order that the user of my invention may represent the outlines of walls, partitions and the like in a manner that pictures truly and exactly the form to be assumed by the finished structure.

By the use of such filaments it is possible not only to bring into relief the outlines of walls, but a discontinuation of the filament between two or more adjoining peg-like members may be used to represent openings in the walls, such as doors, windows, arches, and the like. As the thread-like

55

or filament members are wrapped around and drawn on both sides of the pegs, these filaments will represent floor plan areas, and at the same time will show wall thicknesses, and will define door and window and other architectural openings and features usually desired to be indicated upon a floor plan.

My invention further contemplates the use of peglike members provided with enlarged, flattened tops, upon which tops are to be stamped or printed the names or designations of the several rooms of the building such as, "kitchen," "dining room," etc., and which peglike members shall be placed in holes within the outline established upon my floor planning device in order to show to advantage the relative positions of the several rooms of the building.

Also contemplated by my invention is the provision, along with the base member, filaments, and peglike members, of what I shall call "two-dimensional scaled furniture outlines." The dimensions of these furniture outlines are to be such as to correspond to the scale of measurements of the holes in the base member, thus enabling the user of my device to see how furniture may best be arranged within the various rooms of the projected building.

Many other objects and advantages of my device will be immediately apparent to those versed in the art, among which I wish to point out the use of my apparatus in determining the location, size, and shape of a building, when the dimensions of the plot of land upon which it is to be constructed are known.

In this instance the outline of the plot of ground, or lot may be laid out on the base member by the use of the peglike members and the filaments. It is then possible to plan and adjust the size and shape of the projected building to fit the lot. During this process the thickness of walls and partitions will be readily apparent due to the scaled diametric dimensions of the peglike members, and, through a process of trial and error adjustment, maximum use may be made of all available space both on the building site, and within the outline of the building. It is further possible that peglike members may at this time be placed within the outline of the building site in order to ascertain the landscaping effect and desired position of various trees, shrubs and the like.

With these and other objects in view, some of which will be apparent to those skilled in the art, and others which result from the construction and use of my apparatus, my invention consists of the construction, arrangement and combination of the various parts comprising my device, by means of which the objects contemplated are attained, as will be hereinafter more fully set forth, and which will be better understood by reference to the accompanying drawings.

In the drawings:

Figure 1 is a plan view of my designing and layout device, upon which the floor plan of a building has been reproduced by the means of my invention.

Fig. 2 represents an enlarged portion of the plan view, illustrating a layout that might be used in designing a bathroom, closet or other interior structure.

Fig. 3 is a section on the line 3—3 of Fig. 2, and shows the insertion in the base member of the peglike members and the placement relative thereto of the filamentary members.

Fig. 4 is an enlarged portion of the plan view, showing the positioning of some of the two-

dimensional scaled furniture outlines within the floor plan of a building.

Fig. 5 is a plan view of the two-dimensional scaled furniture outlines.

Fig. 6 is a perspective view of one type of furniture outline.

Fig. 7 and Fig. 8 are perspective views of two types of peglike members.

Fig. 9 is a perspective view of a modified peg-like member used to designate the several rooms of the projected building.

Referring more particularly to the drawings, wherein similar characters of reference denote similar parts, I have shown a base member, substantially rectangular in outline and composed of wood, pressed fiber, metal or other suitable material, into which a plurality of holes have been drilled or otherwise impressed partially therethrough and grouped in such a way as to correspond generally with the rectangular outline of the base member. These holes are regularly spaced one from the other as may be seen by reference to Figure 1, the spacing to be determined by the scale of measurement intended to be used, and are further arranged in a plurality of parallel transversely extending rows. The base member may be of any desired size, and may be constructed and designed for use with any desired architectural or engineering scale.

30 In order to accomplish the design and laying out of a floor plan on base member 1, substantially cylindrical peglike members 2 are provided to be used in defining corners, junctions, wall openings, and other significant points of the design. These members are of a diameter corresponding to the diameter of and yet to be fitted freely within holes 3, so as to permit ready placement in or withdrawal from holes 3. It is intended that these peg 2 shall be of sufficient length to allow a substantial portion to project above the surface of the base 1 when they are fully seated in holes 3 as shown in Fig. 3.

As stated, the base is made of desired size and shape to suit the particular use and the particular scale; and, in the present instance, the illustration may be taken as typical of a base member and associated parts capable of employment in the generally used architectural scale of $1/4''-1'$. For this scale, the holes will be drilled or located on $1/4''$ centers. The substantially cylindrical peg-like members are provided of a diameter to be freely fitted in the holes and to be readily removed; and, with the use of a plurality of pegs it is possible to locate main points or salient dimensions for the outlines of exterior walls, partitions, and the like as it is desired to lay these out. When the pegs are in place with the ends upstanding, the diameter will represent the thickness of a wall, and when the filament or thread-like members are wrapped around and upon both sides of the pegs, such filaments will represent both sides or the thickness of a wall, and at the same time will represent dimensions of rooms and other spaces desired to be indicated.

65 With particular reference to Fig. 2 and Fig. 3, filaments 4, such as string, thread, or rubber bands are supplied to outline walls, partitions and the like. These filaments 4 are to be of a color contrasting with the color of base member 1, so that when secured to and stretched between the pegs 2 as shown, they bring into vivid relief the dimensions and positions of the several portions of the projected structure or other design, and so that the interval between two adjacent, parallel filaments will accurately represent

the scaled-down dimensions of the wall thickness, as at 5.

In Fig. 4, the layout of a room has been accomplished and the arrangement of furniture is being undertaken. Two-dimensional scaled furniture outlines are provided in sizes to correspond to the scale of base member 1, and in the layout shown, scale outlines of a bathtub 6, toilet 7 and wash bowl 8 have been placed on the base member 1, within the outlines of the room, to determine whether the room is of the proper shape and dimensions to contain the furniture and most efficiently serve the purpose for which it was designed.

In Fig. 5 are shown some of the two-dimensional scaled furniture outlines that may be employed in the practice of my invention such as double bed 9, twin bed 10, dresser 11, chest of drawers 12, crib 13, davenport 14, occasional chair 15, lounge chair 16, dining table 17, dining chair 18, bath tub 6, wash bowl 8, toilet 7, kitchen range 19, refrigerator 20, work table and sink 21, the several types of work table 22, 23, 24 and 25, floor lamp 26, console radio 27, and night stand 28. Of course, many other articles may be represented by scaled outlines and I do not limit myself to those above listed.

The two-dimensional scaled outline furniture may be made of any suitable material, preferably light, tough cardboard, and may be furnished as separate pieces, or may, as is well known, be furnished in the form of a sheet upon which are printed, and the outlines perforated, the several articles to be represented.

In Fig. 7, I have shown the peglike member 2 to be used in designating significant points of design, and upon which the filamentary members 4 are placed. Fig. 8 represents a modification of the peglike members in which a slot or cut 29 is provided in the head of the peg 30 along the longitudinal axis in which it is intended that a filament may readily be supported.

In Fig. 9 I have shown an element which is to be used to differentiate the several rooms of a building design. It consists briefly of a supporting member 31, and a flat, head member 32 supported thereon, upon which head member 32 is stamped or imprinted the designation of a particular room 33.

In practicing my invention, the designer, with the base before him as shown in Figure 1, selects a suitable point from which to start the floor plan. A peg is inserted at this point. Using this peg as a reference point, and counting the spaces between holes of vertical or horizontal rows as a measure of scale distance, the designer may then lay out the exterior walls of the building to such dimensions as he deems correct. When the perimeter of the building has been established in this manner it is possible for the designer to place pegs to mark the location of the interior partitions of the several rooms. Pegs may be placed two or more spaces apart to represent openings in the walls and partitions. Filaments are then placed about the proper pegs for exterior walls, partitions, and the like, leaving breaks in the filament at spaces that represent doors and other full openings in the walls. After the filaments are in place on the exterior walls, the designer may insert pegs between such filaments to show the position of windows and similar partial openings.

To identify the functions of the several rooms the designer inserts the peglike identification elements into the base within the outline of the rooms to be designated.

With the basic floor plan thus established, the designer may place the scale furniture within the outlines of the rooms so that the relation of furniture to room may be better realized and, if necessary, modification of the floor plan may be made, thus effecting real savings of time and money while the building is yet in the planning stage.

While the form of my device which I have 10 described and the method I have set forth herein are such as I have constructed and used and have found by trial to be suited to the purposes stated, it will be readily understood by those skilled in the art that my invention is susceptible 15 of various changes and modifications without departing from the spirit and scope explained herein and set forth in the appended claims.

I claim:

1. Means for designing and laying out plans 20 of buildings comprising a substantially flat base member having a plurality of holes therein located and spaced to desired scale dimensions, said openings being of diameter substantially corresponding with wall thickness on the scale adopted, a plurality of substantially cylindrical peg-like members of diameter substantially corresponding to the diameter of the holes insertable in desired plan outline relationship in holes in the base and having their upper ends extending above 25 the top plane of the base, and thread-like members wrapped around and on both sides of the extending ends of the peg-like members in such a way that the space between two peg-like members in the order of the plan is enclosed on both 30 sides by the thread-like member, thus indicating both sides of the wall intended to be shown and giving wall limits of spaces and areas desired to be shown on the plan.

2. Means for designing and laying out plans 40 of buildings comprising a substantially flat base member having a plurality of holes therein located and spaced to desired scale dimensions, said openings being of diameter substantially corresponding with wall thickness on the scale adopted, a plurality of substantially cylindrical peg-like 45 members of diameter substantially corresponding to the diameter of the holes insertable in desired plan outline relationship in holes in the base and having their upper ends extending above the top plane of the base, thread-like members wrapped around and on both sides of the extending ends of the peg-like members in such a way that the space between two peg-like members in the order of the plan is enclosed on both 50 sides by the thread-like member, thus indicating both sides of the wall intended to be shown and giving wall limits of spaces and areas desired to be shown on the plan, and designation carrying peg-like members insertable in certain of the openings of the base member to designate room areas 55 and the like as thus defined by the thread-like members.

3. Means for designing and laying out plans 60 of buildings comprising a substantially flat base member having a plurality of holes therein located and spaced to desired scale dimensions, said openings being of diameter substantially corresponding with wall thickness on the scale adopted, a plurality of substantially cylindrical peg-like 65 members of diameter substantially corresponding to the diameter of the holes insertable in desired plan outline relationship in holes in the base and having their upper ends extending above the plane of the top of the base, thread-like members wrapped around and on both sides 70 of the extending ends of the peg-like members 75 of the

in such a way that the space between two peg-like members in the order of the plan is enclosed on both sides by the thread-like member, thus indicating both sides of the wall intended to be shown and giving wall limits of spaces and areas desired to be shown on the plan, and two dimensional furniture and fixture outline members made to dimensions corresponding to the adopted scale placeable upon the base member within the areas as outlined by the thread-like members.

4. Means for designing and laying out plans of buildings comprising a substantially flat base member having a plurality of holes therein located in parallel transversely extending rows and with individual holes and the rows spaced apart to correspond with desired adopted scale dimensions, said holes being of a diameter corresponding substantially to a wall thickness of the adopted scale, a plurality of substantially cylindrical peg-like members of diameter corresponding to the diameter of the openings insertable in the holes at desired designated planned corner and

opening locations for walls and having their upper ends extending above the plane of the base member, and thread-like members wrapped around and drawn between the cylindrical peg-like members and on both sides thereof to thus give a plan outline and indicate wall thickness.

JOHN D. McCALL.
